United States Patent Office

Des. 202,817
Patented Nov. 9, 1965

202,817

EXTENSION BRACKET

George G. Goda, 390 1st Ave., New York, N.Y.

Filed Dec. 5, 1963, Ser. No. 77,686

Term of patent 14 years

(Cl. D54—13)

Fig. 1.

Fig. 2.

Fig. 3.

FIG. 1 is a top plan view of an extension bracket, showing my new design;

FIG. 2 is a side elevational view thereof;

FIG. 3 is an end elevational view thereof (looking from right to left);

FIG. 4 is a reduced scale side elevational view thereof with its telescopic arms extended full length;

FIG. 5 is a fragmentary isometric view showing a separate specific embodiment of the extension bracket of the claim, wherein an engaging rod to facilitate mounting the bracket is attached to the vertical member holding the extension arms.

The dominant features of the design reside in the portions shown in full lines.

I claim:
The ornamental design for an extension bracket, as shown and described.
